(57) **CLAIM**

The ornamental design for digital audio disk player with
radio tuner and record player, as shown.

DESCRIPTION

FIG. 1 is a perspective view of digital audio disk player with
radio tuner and record player looking from the upper right-
side direction thereof;

FIG. 2 is a front view thereof;

FIG. 3 is a top view thereof;

FIG. 4 is a bottom view thereof;

FIG. 5 is a right-side view thereof;

FIG. 6 is a left-side view thereof;

FIG. 7 is a rear view thereof; and,

FIG. 8 is a perspective view of digital audio disk player with
radio tuner and record player showing the status of opening
of a cover thereof.
